UNITED STATES PATENT OFFICE.

FERDINAND A. WESSEL, OF BROOKLYN, NEW YORK.

ELECTRO-MAGNET.

SPECIFICATION forming part of Letters Patent No. 449,358, dated March 31, 1891.

Application filed November 19, 1890. Serial No. 371,908. (No model.)

To all whom it may concern:

Be it known that I, FERDINAND A. WESSEL, a citizen of the United States, and a resident of Brooklyn, in the county of Kings and State 5 of New York, have invented a certain new and useful Electro-Magnet, of which the following is a specification.

My invention relates to the construction of electro-magnets where it is desired to provide 10 for the division of the coil-winding into sections for any purpose—as, for instance, for varying the power of the magnet.

The invention is applicable to electro-magnets generally, whether stationary or movable 15 and whether provided with a magnetic or a non-magnetic core or carrier, but is especially applicable to stationary magnets having an iron core—such, for instance, as the field-magnets of dynamo-electric generators or motors.

One of the objects of my invention is to secure compactness, smoothness, and uniformity in the windings, and also to facilitate the manufacture.

A further object is to avoid liability to displacement or injury of leading-wires at the 25 point where they lead away from the coils.

Another object is to permit the division of the coils into sections, each consisting of a single layer of wire, and at the same time to 30 carry all the leading-wires away from the coils at the same edge.

Other advantages secured by my invention will be apparent to those skilled in the art.

My invention consists, first, in disposing the 35 leading-wires where they lie outside of the coil in a flat layer resting directly upon the pole or an extension of the core, the wires of such layer being all disposed in a plane parallel with the surface on which they lie. By 40 this means all the wires hug the surface closely, and, not being separate therefrom, are less liable to be caught by foreign objects.

Another part of the invention consists in carrying the leading-wires for the coils beneath 45 said coils, between the coils and core or carrier, and across the coil-space, as herein-after described.

The invention consists, further, in building the coil by placing the leading-wires in position, winding the coils as a continuous winding, and during the operation making con-

nexion to the leading-wires at the proper points in the winding.

Other features of improvement constituting my invention will be described in connection with the accompanying drawings, and then specified in the claims.

In the accompanying drawings, Figure 1 is a plan of an electro-magnet having its leading-wires disposed in accordance with my invention and showing the beginning of the winding on the first layer or coil-section. Fig. 2 shows the magnet with the first layer wound and with the first turn of the second layer or section of coil applied. Fig. 3 is an end view 65 of the magnet, and Fig. 4 an edge view of the same. Fig. 5 is a diagram.

A indicates the magnetic core of an electro-magnet—such as the field-magnet of a motor—and B B coil-heads or flanges, which, 70 in carrying out my invention, may be either temporary heads or flanges located at opposite edges of the coil-space, or may be the spool-heads or flanges of the finished magnet which hold the coils in place.

The leading-wires for the sectional coil are indicated by the letters *a a'*. These wires rest upon the pole or core extension of the electro-magnet, as shown more clearly in the edge view, and are assembled thereupon in a 80 flat layer, the wires of which lie in a plane parallel to the face of the pole or core extension. Being thus arranged, they are less liable to displacement or derangement, and their ends may be carried over the end of the pole-piece and attached to switch-blocks or other devices mounted upon the pole.

To construct a sectional coil in accordance with my invention I proceed as follows: The leading-wires *a a'* are assembled in position 90 upon the core or carrier A for the coils, with their free ends, which are to be connected to the coil-sections, upturned, as indicated in Figs. 3 and 4. The leading-wires which are to be connected with the edge of the coil at 95 the edge thereof next the pole-piece are indicated by the letter *a*, and those which are to be connected with the coil at the opposite edge by the letter *a'*. As shown, the alternate leading-wires extend across the space 100 occupied by the coil, and being so placed all the coil-windings will be wound over them.

The heads or flanges B are provided with suitable recesses, as indicated at b, to receive the upturned ends of the wires a a'. In beginning the winding the beginning of the coil 5 is connected to the end of the first leading-wire a, the upturned end of which is bent down, as indicated in the figures, so as to lie parallel with the wire constituting the coil. Connection may be made by bearing the insulation on the coil-wire and binding and soldering, as well understood in the art. One or more layers of wire are now wound continuously upon the core A, and at the completion of the first, third, or other winding, which 10 15 terminates at the edge of the coil-space where the leading-wires a' are upturned, the first of the upturned ends of the latter wires is bent down and connection made to the coil-winding.

I prefer in constructing the coil for many 20 purposes to wind but a single layer, and will assume in the future description that the sectional magnet has sections each consisting of a single layer.

Fig. 1 shows the beginning of the operation of winding, two complete turns having been applied to the coil, and the wire being shown as starting on the third turn. Proceeding in the ordinary way, a single layer of wire is laid over the whole space A until the 25 30 35 winding progresses so that the wire lies next to the head of the coil, where the upturned ends of the leading-wires a' are located. The last turn is indicated by the numerals 5 6, Fig. 2, the part 5 thereof constituting the last end of the first turn, and the part 6 thereof, which is continued into turn 7 as the first turn of the second layer, constituting the beginning of the second section. The first turn 7 is, for the sake of illustrating the idea, 40 shown as to one side of the turn 5 6; but it will be understood that in practice it would be wound on top of the turn 5 6, the windings being continued for the second section in reverse order on top of the windings of the first layer or section. When the end of the 45 50 55 wire of the first layer has been brought to the position upon the core indicated at 5 6, the end of the first leading-wire a' is turned down and connected thereto, as indicated. After the connection has been completed the wire is given another turn, resulting in the turn 7, just described, which makes the first 60 65 70 turn of the second layer. This layer is now wound, the wire being applied on top of the first layer and progressively filling the space in a reverse direction, just as thread is wound upon a spool. When the second layer has been filled out to the opposite head B, so that the wire lies next to the head, where the upturned ends of the leading-wires a are located, the second of said wires a is turned down just as the first was and connection made to the last turn of the second layer. The winding is then continued and the first 75 80 85 turn of the third layer is wound upon the top of the last turn of the second layer and the third layer is applied, filling the space pro-

gressively until the wire reaches the head, where the terminals a' are located, when connection is made to the wire by bending down 70 the second of the wires a', just as the first was bent down and connected. The operation is then continued, passing from one side to the other of the coil-faces without interrupting the continuity of the wire which is wound upon 75 the spool or magnet-core, connection being made, however, to said wire at intervals, as already explained, by bending down and soldering the terminals of the leading wires. The operation is continued until the last of the wires 80 a is reached, when connection is made to the ends of the top layer, the last leading-wire a constituting, therefore, the terminal of the whole series of coil-sections. When connection has been made at this point, the end of the wire 85 applied to the core is cut off and the operation completed by covering the joint, shellacking and applying whatever protecting - envelope may be desired, as well understood in the art. As each leading-wire a a' connects to 90 the end of one coil and the beginning of another, it will be obvious that by providing thirteen (13) wires, as shown, a coil of twelve (12) sections may be wound.

When the winding proceeds in the manner 95 just described, the first of the wires forms one pole or terminal of the series of sections and the last wire a would form the end or opposite terminal of the series, while the remaining wires a, five in number, together with the 100 six wires a', would form connections to intermediate portions of the sectional winding, as illustrated in Fig. 5.

The head or flange B next the pole end of the magnet is provided with a slot near its 105 inner edge, as indicated in the end view, said slot being parallel to the pole-face of the core, as shown, to afford a passage for the leading-wires, which all rest upon the core or carrier. The recesses b afford a space for the ends of 110 the leading-wires when they are turned down for connection with the coil-windings.

What I claim as my invention is—

1. In a sectional electro-magnet, a retaining head or flange for the coils, having an elongated slot or opening near its inner edge and parallel to the face of the pole or core, in combination with leading-wires for the coil-sections passing through said slot and resting upon the pole-face in a single flat layer. 115
2. In a sectionally-wound electro-magnet, leading-wires resting upon the core or carrier upon which the coils are wound beneath said coils and extending across or transversely to the coils from one edge to the other of the coil-space. 120
3. In a sectionally-wound electro-magnet in which each layer of wire constitutes a separate section, leading-wires for the alternate sections extending beneath all the windings 130 to the opposite side of the magnet-coil.
4. In a sectionally-wound electro-magnet, leading-wires assembled in a parallel plane upon the core or carrier for the coils and con-

nected alternately to the windings at opposite edges of the coil.

5. In a sectional electro-magnet, leading-wires passing through the coil head or flange near the core or carrier, the alternate wires being extended across to the opposite edge of the coil for connection with the edge of a layer of the winding.

6. In a sectional electro-magnet, a series of leading-wires connected to the coil-sections and carried beneath the coils between the same and the core or carrier upon which they are wound.

7. The herein-described method of constructing a sectional electro-magnet, consisting in placing the leading-wires in position upon the core or carrier for the coils, with free ends at opposite sides of the space to be occupied by the said coils, winding the wire upon the carrier as a continuous coil, and during the operation connecting the leading-wires to the same at the edges of the layers.

8. The herein-described method of constructing a sectional electro-magnet, by placing the leading-wires in position with their ends upturned at the edge of the coil-space, winding the wire as a continuous coil, and on the completion of a layer bending down an

upturned end of a leading-wire in a plane parallel to the plane of winding and connecting to the coil at the edge thereof.

9. The herein-described improvement in constructing a sectional electro-magnet, consisting in placing the leading-wires in position, winding the coil, and making connection to the leading-wires as the winding progresses.

10. The herein-described improvement in constructing sectional magnetic coils, consisting in placing the leading-wires in position with the alternate wires extending across the pole-space, applying the coil-winding, and connecting the edges of the layers alternately to the free end of the leading-wires at opposite sides of the coil-space.

11. In a sectional electro-magnet, spool-heads or flanges provided with recesses *b* next the coil-windings to receive the ends of the leading-wires.

Signed at New York, in the county of New York and State of New York, this 1st day of November, A. D. 1890.

FERDINAND A. WESSEL.
